HARNESS FRAME FOR LOOMS

Paul C. Consoletti, Milford, Mass., assignor to
 Draper Corporation, Hopedale, Mass., a corporation of Maine

Application February 18, 1950, Serial No. 144,972

11 Claims. (Cl. 139—92)

1

This invention pertains to improvements in harness frames for looms.

It is an object of the invention to devise a harness frame for looms which shall be more compact, shall be of light weight, yet strong and rigid thereby to resist stresses set up during operation thereof in modern high speed equipment, and to devise such a frame from light alloys now available at a relatively low cost.

It is a more specific object of the invention to devise a harness frame which shall be adapted to facilitate drawing in of the warp by one of the well known drawing-in machines now commonly employed.

Another object of the invention is that of devising a harness frame in which the heddles shall be freely slideable from one end to the other of the frame and in which these heddles shall be mounted on hardened steel or other equivalent bars or supports retained in a light alloy structure which would not in and of itself be suitable for directly supporting the heddles.

It is a further object of the invention to devise a harness frame of the type described which shall provide for positively supporting the heddle carrying bars or rods throughout substantially their entire length, but which shall provide for ready removal of heddles from the frame or of the heddle carrying bars therefrom with a minimum of effort and without special tools.

Other objects will become evident from the following more detailed description.

Harness frames have, with a few exceptions, been constructed of wood with metal rails being employed for retaining the heddles themselves and along which the heddles may move. Obviously, there are certain disadvantages in the use of wood since it is subject to the action of moisture and these harness frames which must necessarily be relatively thin and therefore made from thin strip material, frequently warp out of shape and become so distorted that the movement of the frames in the loom, the free movement of heddles along the supporting rails therein and especially, the manipulation of the heddles during drawing in a warp by one of the well known drawing-in machines becomes increasingly difficult. In obviating these and other disadvantages attendant upon the employment of wood or of frames partially made from wood, the instant invention is devoted to the construction of a frame entirely of metal and which is therefore not at all subject to the influences of moisture and which will retain its rigidity, strength and initial shape and dimensions throughout a long period of use.

2

The preferred form of harness frame according to the invention is constructed from extruded light alloy sections such as aluminum alloy extrusions and cast aluminum parts employed therewith and connected thereto by riveting, or in any other satisfactory manner. The particular shape and dimensions of the said extruded parts are so proportioned as to reduce the overall height of the frame while increasing its strength and rigidity and, in fact, the frames devised as hereinafter described in greater detail are adapted to withstand considerable use and abuse without any likelihood of their becoming unsuitable or unfit for operation.

10 The heddles are carried on upper and lower strips or bars which are preferably of hardened steel of a type which is highly resistant to wear and is not adversely affected by the heddles which are constantly being moved up and down by the harness mechanism and which therefore have a tendency to impact their supporting bars and also to move laterally thereon throughout a limited extent. These supporting bars are, contrary to the common practice heretofore employed, supported throughout their entire length and retained laterally throughout practically or substantially the entire length thereof by an integrally formed part of the extruded metal frame members in which they are seated when the entire assembly has been completed.

15 These heddle supporting bars are quickly removable, but are retained by means of latch members carried within suitable recesses in the end struts of the frame and which when locked in position, cannot become accidentally loosened nor will they permit the heddles threaded thereon to move beyond their intended range. This construction provides for threading or carrying the heddles on a continuous, unobstructed guide means by which said heddles may be slid freely from one side of the frame to the other and thus the bars, while supported rigidly along substantially their entire length, are not in any way obstructed insofar as the heddle carrying surfaces of the bars are concerned.

20 While the preferred form of the invention is devoted to a frame in which the structural members are either extruded or cast of light aluminum or other alloys, similar advantages are to be obtained when the frame is fabricated from rolled or other steel or sheet material as will hereinafter be described in detail. The support of the heddle frames themselves by the harness mechanism is conveyed to the frame through 25 certain connecting means which are attached to top and bottom frame rails or to ribs or strips

thereon which may preferably have enlarged or beaded portions to which the strap connections or hangers are readily attached and from which they may be detached at will.

The invention will hereinafter be described in greater detail by reference to the accompanying figures of drawing wherein:

Fig. 1 is an elevation showing a complete harness frame with heddles constructed in accordance with the invention.

Fig. 2 is a section through one of the rails of the harness frame of Fig. 1, said section being taken at line 2—2.

Fig. 3 is a corresponding section, but showing a modified construction in which rolled steel is used in the place of extruded aluminum.

Fig. 4 is a detail view of one of the end struts and a latch carried within a recess in said strut.

Fig. 5 is a section at line 5—5, Fig. 4.

Now referring to Fig. 1, the harness frame comprises top and bottom rails 10 and 11, end struts 12 and 13 and heddle supporting bars or rods 14 and 15. The frame is suspended between harness mechanism of the conventional type which is attached to the frame by connecting means one form of which is indicated as a clamping member 16 having an eye or loop 17, each of the clamping means being fixed to a beaded rib 18 which forms an integral part of the extruded section, although it is to be understood that the particular connections by means of which the frame is suspended forms no particular part of the invention herein described and claimed and therefore need not be disclosed in any particular detail.

Heddles 19 are preferably formed from flat stock and may be of conventional type so long as they are adapted to be hooked over supporting bars 14 and 15 as illustrated in Fig. 2. These heddles are preferably of a type adapted to function with existing drawing-in machinery such as the well known Barber-Coleman drawing-in machines and since their function is well known and since heddles of a type adapted to be employed with these drawing-in machines are readily available, they need not be described in detail here.

Now referring to Fig. 2, one of the rails 10 or 11 is illustrated in section and it is to be understood that the section as shown here is one which has been found to serve quite satisfactorily, but that various changes may be effected and the dimensions thereof may be altered within limits without departing from the original inventive concept and while still retaining the advantages peculiar to the invention as herein described. This rail 10 has a hollow rectangular portion 20 which imparts to the structural form a definite amount of rigidity and since it is a box section, it resists torsional forces to a considerable extent. The rib 18 has a web 21 and a beaded portion 22 and extends outwardly, that is, upwardly at the top of the frame, and downwardly at the bottom, since these rails 10 and 11 are oppositely directed as illustrated in Fig. 1, and they serve to connect or attach the suspending means 16 and 17 which are preferably clamped to the beaded portion of the rib so as to be maintained permanently in position. Normally four suspending means are employed, two at the top and two at the bottom, although the particular number is not limited thereto and may be varied at will.

The extruded section includes in addition to the parts already mentioned a web 23 which continues from one side of the hollow, rectangular,

box-like portion of the form and terminates at its free edge in an enlarged portion in which is formed during the extruding operation, or in any other satisfactory manner, a groove 24 for the reception of the heddle carrying bar 14 or 15, as the case may be. It also comprises a ribbed or bulbous extension 25 which serves as a track for the heddle backer of the drawing-in machine. That gives an additional and precisely located guide means independent of the heddle carrying bars or rods themselves.

Preferably the groove 24 is inclined slightly as illustrated in Fig. 2 so that the heddle carrying bar inserted in that groove may incline slightly to provide sufficient space between the bar and the face of the web 23 for ready sliding movement of the hooked ends 26 of the heddles 19. As an alternative, the groove may not be inclined while the bar may be bent slightly so its disposal beyond the groove is one in which it is inclined or offset to permit the heddles to be threaded and to slide with adequate clearance. The parts just above described are susceptible of varying forms and dimensions, but the general principles remain the same and it is not considered necessary to illustrate any of the different forms of the bar 14 or of the supporting structure in which it is carried at this point.

Now referring to Fig. 3, a similar top or bottom rail is shown, this rail having been formed of steel and being of relatively thin section. The fabrication of the rail may be by pressing and rolling the stock to shape, and, in certain instances, welding of the parts may be resorted to if desired. The rail comprises a hollow portion 27 which is closed as the edge 28 of the stock is brought into contact with the material adjacent the web 29 and this web is bent into proper form at its free edge to present a groove 30 in which the bar 14 is supported, it being evident that the general shape and function of the rolled steel form is similar to that provided by the light metal extrusion. In Fig. 3 no connecting means is illustrated but suspending hooks may be attached to the hollow structural form 27 in any convenient manner.

It is to be noted that, as illustrated in Fig. 2, the front edge 31 of the relatively free edge of the web 23 extends upwardly far enough to embrace the bar 14 and to support it rather rigidly in proper angular position. This front extension, however, is terminated a short distance from the ends of the rails to permit the heddle carrying bars 14 or 15 to be bent outwardly or forwardly as the frame is viewed in Fig. 1 so as to remove or replace these bars or to thread or remove heddles therefrom when the ends of the bars have been unlatched as will hereinafter be described. Preferably, the ends of each bar are bent outwardly as shown in dot-and-dash lines in Fig. 5, so they tend to snap out of line beyond the face of the frame to permit removal or threading of the heddles. This initial flexure imposes a pressure on the latch means to keep it from loosening. The bars are thus supported through substantially their entire length by the rails 10 and 11 and this supporting structure embraces both sides of the bars for an appreciable extent as well as sustaining them from beneath, or from above, as the case may be. This provides an extremely rigid construction and does not necessitate any depending hook members or spaced attachments for the heddle carrying bars such as have heretofore been employed, while at the same time, the frame assembly permits free movement of any

or all heddles from one end of the frame to the other since there are no obstructions whatsoever to their being slid along their respective bars, this being an advantage in that there is no tendency of the heddles to be crowded to one side or the other of the bar suspending or attaching means as may well be experienced when these bars are not supported throughout their entire length since they must then be subjected to some appreciable amount of deflection.

The end struts 12 and 13 are preferably formed of cast aluminum alloy, although other metals or materials may be employed, and the attachment by means of rivets 32 serves very satisfactorily, although other connecting means may be utilized. These end struts are recessed as at 33, Figs. 4 and 5, for the reception of bar retaining means in the form of a quickly releasable latch member such as that illustrated, although it is to be understood that the particular form which this latch means may take is not in and of itself a part of the instant invention.

The recess 33 is disposed between the side ribs 34 and 35 which are, of course, integral parts of the strut 13 and the inner rib such as 35 is notched as illustrated at 36, Fig. 5, for the reception of the end of bar 14. These bars 14 and 15 are long enough to overlap the end struts as shown, but fit within the notches 36 and do not extend quite to the opposite edge of the recesses 33 or to the outer rib members such as the rib 34. The latch means more completely shown and described in United States Patent No. 2,556,468 comprises a swinging detent 37 pivoted on a rivet 38 or other suitable pivot means extending through the ribs 34 and 35 and having a hook 39 at its free end. This detent is so pivoted and so shaped as to press against the flat side of the bar 14 or 15, as the case may be, and retain it inwardly against the back edge of the notch 36.

The other portion of the latch means comprises a hook 40 pivoted on the central portion 41 of a wire bail 42 the opposed ends 43 and 44 of which extend through suitable apertures in the side ribs 34 and 35. This hook is bent over as at 45 to engage the hook 39 of the detent and is also provided with an end extension or thumb piece 46 which serves to release the detent and to permit the hook 39 to be moved outwardly from the recess. This is normally done by hand or a suitable tool may be employed to pry the thumb piece outwardly whereupon the entire mechanism may be released and swung to a position in which the hook end 45 disengages the hook end 39 and the detent may be swung upwardly to free the end bar 14. As illustrated in Fig. 5, the bail 42 swings past a dead center position as the parts are latched so that they are resiliently retained in position since the dimensions of the parts are such that when in the latched position the inherent spring or resilience of the members is brought into play to retain them against accidental displacement. As the tail piece or thumb latch 46 is pulled forwardly the bail swings past its central position and tension on the parts is released.

One of these latch means is provided at each of the four corners of the frame and the bars 14 and 15 retained in position thereby may be released and removed, or may be released so the bar ends may swing outwardly to permit threading or removal of a heddle or heddles.

The bars upon which the heddles are carried may be hardened as stated, or may be stainless steel which will stand the action of the heddles

quite well. It may be chromium plated if desired to present a hard smooth surface for greater ease in threading or removing heddles. The bar may be reversed to employ both sides.

From the above description the manner in which the various parts of the frame are disposed or manipulated during threading on or removing heddles and the way it functions during drawing in a warp should be evident. The frame is set up in the drawing-in machine as usual and the free movement of heddles from one end to the other facilitates the work of that machine.

In the appended claims reference is made to "inner" and "outer" portions of the rails. These subdivisions refer to the part of the rail within the hollow rectangle formed by the frame and to the top and bottom, peripheral parts thereof, respectively. For example, the grooves in which the heddle bars are seated open in the direction of the outer portion of the rail or away from the inner or more centrally located part thereof.

While one embodiment and a modification of the invention have been disclosed, it is to be understood that the inventive concept may be carried out in a number of ways. This invention is, therefore, not to be limited to the precise details described, but is intended to cover all variations and modifications thereof falling within the spirit of the invention and the scope of the claims.

I claim:

1. In a harness frame for looms the combination of top and bottom rails and end struts interconnected to form a rigid, rectangular frame, each said top and bottom rail being of relatively rigid, deflection resistant section the inner portion of which comprises a web and a bulbous edge portion grooved throughout a substantial part of its length, said groove being open in the direction of the outer portion of the rail a heddle supporting bar directly seated in said groove and extending into said end struts, and a latch means carried by each said end strut and engageable with the end of said bar therein for releasably retaining it in position.

2. In a harness frame for looms the combination of top and bottom rails and attached end struts which, when assembled, comprise a rigid rectangular frame, each said top and bottom rail being formed as a hollow section from which projects an integral web portion with its relatively free edge grooved throughout a substantial portion of its length, said groove being open in the direction of the outer portion of the rail a heddle supporting bar directly seated in said groove, and latch means for retaining the ends of said bar, said latch means being readily releasable to permit removal of the bar.

3. In a harness frame for looms the combination of top and bottom rails and attached end struts which, when assembled, comprise a rigid, rectangular frame, each said top and bottom rail being formed as a deflection resisting, structural shape a portion of which extends toward the center of the frame as a web the relatively free, inner edge of which is formed to provide a groove extending along substantially the entire mid section of the frame to a point at each end closely adjacent the end struts, said groove being open in the direction of the outer portion of the rail a heddle supporting bar directly but removably seated in said groove, and latch means at the bar ends and carried by the end struts for locking the bar in position, but permitting its ready release for removal.

4. In a harness frame for looms the combination of top and bottom rails and attached end struts which, when assembled, comprise a rigid, rectangular frame, each said top and bottom rail being formed as a hollow section from which projects an integral web portion with its relatively free edge grooved for a substantial portion of its length, said groove being open in the direction of the outer portion of the rail a heddle supporting bar directly seated in said groove, notches in said end struts into which the ends of said bar extend for limiting the movement of the bar in a direction parallel to the length of the struts, and latch means for releasably retaining the said ends of the bar in said notches.

5. In a harness frame for looms the combination of top and bottom rails and attached end struts which, when assembled, comprise a rigid, rectangular frame, each said top and bottom rail being formed as an extruded, light metal section including a web portion the relatively free edge of which is grooved for a substantial portion of its length, said groove being open in the direction of the outer portion of the rail a hardened steel heddle supporting bar directly seated in said groove, and means including a releasable latch means at each strut for engaging an end of the bar and retaining it in said groove.

6. In a harness frame for looms the combination of top and bottom rails and attached end struts which, when assembled, comprise a rigid, rectangular frame, each said top and bottom rail being formed as an extruded, light metal section comprising a hollow box portion, a suspending rib and a web the free edge of which is grooved for a substantial portion of its length intermediate its ends, but is open at one side for a short portion of its extent at each end, said groove being open in the direction of the outer portion of the rail a hardened steel heddle supporting bar directly seated in said groove, and means including a releasable latch means at each strut for engaging an end of the bar and retaining it in said groove.

7. In a harness frame for looms the combination of top and bottom rails and attached end struts which, when assembled, comprise a rigid, rectangular frame, each said top and bottom rail being formed as an extruded, light metal section including a web portion the relatively free edge of which is grooved for a substantial portion of its length, said groove being open in the direction of the outer portion of the rail a hardened steel heddle supporting bar directly seated in said groove, notches in said end struts aligned with said bar when it is fully seated in the groove into which the ends of the bar are received, recesses in said struts adjacent the said notches, and means for releasably locking the bar ends in their notches, said means comprising latches positioned in said recesses.

8. In a harness frame for looms the combination of top and bottom rails and attached end struts which, when assembled, comprise a rigid, rectangular frame, each said top and bottom rail being formed as an extruded, light metal section including a web portion the relatively free edge of which is of enlarged, bulbous form, a groove therein the front wall of which is discontinued adjacent the ends of the rail to permit

the ends of the bar held in the groove to be flexed beyond the face of the frame during insertion or withdrawal of the bar, notches in said end struts aligned with said bar when it is fully seated in the groove into which the ends of the bar are received, recesses in said struts adjacent the said notches, and means for releasably locking the bar ends in their notches, said means comprising latches positioned in said recesses.

10. In a harness frame for looms the combination of top and bottom rails and end struts interconnected to form a rigid, rectangular frame, each said top and bottom rail being of relatively rigid, deflection resistant section a portion of

15 which comprises a web and a bulbous edge portion grooved throughout a substantial part of its length, said groove being open in the direction of the outer portion of the rail a heddle supporting bar directly seated in said groove and extending into said end struts, the ends of said bar beyond the point of termination of said retaining groove being initially bent to spring outwardly, and a latch means carried by each said end strut and engageable with the end of said bar 20 therein for releasably locking it in position.

25 10. In a harness frame for looms the combination of top and bottom rails and attached struts which, when assembled, comprise a rigid rectangular frame, each said top and bottom rail being formed as a hollow section from which projects an integral web portion with its relatively free edge grooved throughout a substantial portion of its length, said groove being open in the direction of the outer portion of the rail a track-like bead adjacent the said edge serving as a guide 30 means for a heddle backer of a drawing-in machine, a heddle supporting bar directly seated in said groove, and latch means for retaining the ends of said bar.

35 40. 11. In a harness frame for looms the combination of top and bottom rails and end struts interconnected to form a rigid, rectangular frame, each said top and bottom rail being of relatively rigid, deflection resistant section a part of which 40 comprises a web and a bulbous edge portion grooved for a part of the extent of its length, said groove being open in the direction of the outer portion of the rail a heddle supporting bar directly seated in said groove, said bulbous edge 45 portion further being so formed as to present a track-like bead which serves as a guide means for a heddle backer of a drawing-in machine.
